UNITED STATES PATENT OFFICE.

WILLIAM B. ROGERS, OF OLEAN, NEW YORK.

HYDROCARBON-BURNER.

1,160,765.

Specification of Letters Patent. Patented Nov. 16, 1915.

Application filed March 26, 1915. Serial No. 17,148.

To all whom it may concern:

Be it known that I, WILLIAM B. ROGERS, a citizen of the United States, residing at Olean, in the county of Cattaraugus and State of New York, have invented new and useful Improvements in Hydrocarbon-Burners, of which the following is a specification.

This invention relates to the class of burners which are employed for burning liquid fuel, such as kerosene and other crude oils, and more particularly to a burner of this kind which is designed for cooking and heating stoves, although it may be used for other purposes, if desired.

One of the objects of my invention is to improve the construction of the air-supplying devices of the burner with a view of insuring perfect combustion and producing a hot and smokeless flame.

A further object is the provision of a simple burner of this class which can be cheaply produced and easily installed.

In the accompanying drawings: Figure 1 is a vertical longitudinal section of the fire box of a cooking stove equipped with the improved burner. Fig. 2 is a horizontal section of the burner on line 2—2, Fig. 1. Fig. 3 is a transverse central section thereof.

Similar characters of reference indicate corresponding parts in the several views.

1 indicates the fire box of a coal or wood burning stove, which, in the example shown, has an ordinary grate 2.

The improved burner comprises a hollow base 3 resting upon the grate and constructed of suitable dimensions to form a comparatively large air chamber. It is open at its bottom and provided in its closed top with an upwardly-extending mixing tube 40 or collar 4 which opens at its lower end into the hollow base and at its upper end into the fire box. The portion of the grate not occupied or covered by the hollow base is preferably closed by cement 5 or other suitable sealing material to compel the air under the grate to ascend only through the base and its collar 4. Arranged within this collar is the burner proper 6, which preferably consists of the lower horizontal branch of a U-shaped

50 pipe, the upper branch 7 of which is arranged directly over the branch 6 and forms a vaporizer for the kerosene or other liquid fuel which is supplied thereto from a tank or other source of supply, not shown. The 55 pipe 7 is provided on the outside of the stove with a valve 8 to regulate or shut off the

supply of oil. The burner pipe 6 is provided in its upper side within the collar 4 with one or more jet openings 6^a for the oil-gas. Directly above said collar is a suitable flame-spreader 9 which in the preferred construction shown in the drawings, is hollow and consists of a circular horizontal chamber 10 interposed in the pipe 7 and forming practically an enlargement thereof. The liquid fuel entering through the pipe 7 is vaporized in a well known manner by contact with the walls of said pipe and the chamber 10, which parts are heated by the flame of the main burner 6, after said pipe and chamber have been preliminarily heated by the customary supplemental burner with which such devices are provided. This supplemental burner forms no part of my invention and may consist of a wick 11 of asbestos or other suitable material seated in a groove 12 formed in the top of the base 3 around the collar 4 and adapted to be saturated with oil or other fuel.

In the construction shown, the burner pipe 6 extends through openings in opposite sides of the mixing collar in which it is clamped by set screws 13 or other appropriate means.

The air ascending into and through the open-bottomed base 3 enters the collar 4 and commingles with the jet of vaporized fuel or oil-gas escaping from the burner pipe, the collar thus forming a mixing chamber, whereby the air is brought into close and intimate contact with said jet.

As shown in the drawings, the base 3 and collar 4 are both tapered upwardly. By this construction, the upward air current through the grate is condensed between the upwardly-converging walls of the base and the collar and therefore accelerated, producing an increased draft through said chamber which materially promotes combustion.

It has been found that by the use of this burner the combustion of the vaporized jet is so complete and perfect as to produce a steady, blue and smokeless flame which is intensely hot, rendering the burner especially desirable for ordinary coal and wood burning stoves used for cooking and heating purposes.

While the oval or oblong form of the base 3 shown in the drawings is preferred, the same may be circular or of any other suitable shape, if desired.

As regards the construction of the combined flame spreader and vaporizer, it has

been found that the most satisfactory results are obtained when the same is substantially of the same diameter as the upper end of the collar or mixing chamber 4, as shown 5 in the drawings.

As the hollow spreader constitutes an enlargement of the fuel-pipe which is located where the heat from the burner is most intense, it is practically impossible for the fuel 10 to pass through said pipe without being thoroughly vaporized.

The simplicity of the burner renders it inexpensive and enables it to be easily installed, only a single opening in a convenient 15 wall of the fire-box being required for the entrance of the vaporizing pipe 7.

I claim as my invention:

1. A hydrocarbon burner, comprising an air chamber open at its bottom and provided 20 in its top with an open-ended collar forming a mixing chamber, a burner-pipe arranged in said mixing chamber, a fuel-pipe leading to said burner-pipe, and a vaporizing cham-

ber of substantially the same diameter as said mixing chamber arranged directly over 25 the latter, said vaporizing chamber forming an enlargement of said fuel-pipe.

2. A hydrocarbon burner, comprising an upwardly-tapering hollow base open at its bottom and forming an air chamber, an upwardly-tapering open-ended collar communicating with the top of said base, a burner-pipe arranged within said collar, a fuel-pipe leading to the burner-pipe and arranged above the same, and a combined flame 35 spreader and vaporizing chamber arranged directly over said collar and constructed of substantially the same diameter as the small end thereof, said vaporizing chamber forming an enlargement of said fuel-pipe. 40

Witness my hand this 9th day of March, 1915.

WILLIAM B. ROGERS.
